(57) **CLAIM**

The ornamental design for a cookie package as shown and described.

DESCRIPTION

The file of this patent application contains a color figure. Color is an integral part of the design shown in this Figure. Copies of this patent with color drawing will be provided by the Office upon request and payment of the necessary fee. The sole FIGURE is a front view of a cookie package, showing our new design.

The dash-dot-dash lines shown in the drawings depict the boundary of the claimed design and form no part of the claimed design. The dashed lines shown in the drawings depict portions of the cookie package that form no part of the claimed design.
